UNITED STATES PATENT OFFICE.

RUTHERFORD B. CHASE, OF CHICAGO, ILLINOIS.

CLEANING AND POLISHING APPARATUS.

1,350,403.

Specification of Letters Patent. Patented Aug. 24, 1920.

Application filed August 14, 1919. Serial No. 317,476.

To all whom it may concern:

Be it known that I, RUTHERFORD B. CHASE, a citizen of the United States, and a resident of the city of Chicago, in the county of Cook and State of Illinois, have invented certain new and useful Improvements in Cleaning and Polishing Apparatus; and I do hereby declare that the following is a full, clear, and exact description of the same, reference being had to the accompanying drawings, and to the numerals of reference marked thereon, which form a part of this specification.

This invention relates to a cleaning, polishing and similar apparatus, and although not limited to such use, is particularly adapted for use in cleaning the type matrices employed in linotype machines.

In the operation of linotype machines it is found that the matrices become dirty and sticky so that they do not slide into place readily and in some cases do not fit the frames properly.

One of the objects, therefore, of this invention is to provide a machine for cleaning type matrices.

Another object of the invention is to provide means for preventing wear on the letters on the matrices during the cleaning operation.

A further object of the invention is to provide a machine for not only cleaning type matrices, but also for performing many other operations connected with linotype, typesetting and printing establishments, such as grinding, milling or drilling.

Other and further important objects of this invention will be apparent from the disclosures in the drawings and specification.

The invention (in a preferred form) is illustrated in the drawings, and hereinafter more fully described.

On the drawings:

Figure 1 is a side elevation of a machine constructed in accordance with the present invention.

Fig. 2 is a plan view of the same.

Fig. 3 is a section on the line 3—3 of Fig. 1.

Fig. 4 is a section on the line 4—4 of Fig. 1.

Fig. 5 is a plan view of the matrix holder with the cover removed.

Fig. 6 is a plan view of the cover of the matrix holder. 55

Fig. 7 is an elevation of one end of the matrix holder.

Fig. 8 is an elevation of the other end of the matrix holder.

Fig. 9 is a side elevation of the matrix holder. 60

Fig. 10 is a section on the line 10—10 of Fig. 9.

Fig. 11 is a section on the line 11—11 of Fig. 8. 65

As shown on the drawings:

The whole machine is carried by a standard 1, carrying at its upper end an electric motor 2. The casing of this motor is provided with a depending rod 3, slideable vertically in the standard 1, so that the height of the motor may be adjusted vertically. 70

If desired, the height of the motor 2, may be adjusted without preventing angular movement of the motor about the axis of the standard 1. This may be accomplished by providing a collar 27, adapted to rest on the top of the standard and to be secured to the rod 3, by a set screw 28 at any desired position therealong. In the construction shown, an oil pan 29, is formed integrally with the collar 27, to catch any drippings from the motor. 75

The shaft of the motor extends some 85 distance therefrom and is supported by an extension 5, of the motor casing. To the end of this shaft a buffing wheel 6, or the like, may be clamped by means of the nut 8 and washer 9, which presses the wheel 90 against a flange 10, on the shaft.

Beneath the wheel 6, a support 7, is arranged, carried by a bracket 11, pivotally connected to a collar 12, on the standard 1. This collar 12 is made in two halves connected by bolts 13, so that the collar may be arranged to grip the standard at any desired height or angular position. 95

The pivotal connection between the bracket 11 and collar 12, comprises a pair 100 of lugs 14 on the bracket, and a lug 17 on the collar, through which passes a bolt 15, forming the pintle of the hinge. By tightening the nut 16 on this bolt, the latter may be non-rotatably secured to the lugs 14 105 without restricting the swinging movement

of the bracket. However, by tightening a set screw 18, passing through the lug 17, the bolt 14 may be locked to the latter and any swinging movement of the bracket prevented.

A cylindrical boss 19 is formed at the outer end of the bracket 11, for the reception of a stub shaft 20, secured to, or preferably made integral with the support 7.

10 The position of the shaft 20, in the boss 19, may be adjusted by a screw 21 passing through and having threaded engagement with the lower part of the boss 19. This screw may be locked in adjusted position 15 by means of the nut 22.

The stub shaft 20 is free to rotate in the boss 19, and may lift away from the end of the screw 21 so that to secure it in position both angularly and axially a set screw 23 20 may be provided.

Upon this support 7, a table 24 or other device such as a vise or clutch may be arranged. This table may conveniently be formed with a projection 25, adapted for 25 sliding engagement with a dove-tail channel 26, in the upper surface of the support 7.

Upon the table 25 are placed the type matrices to be cleaned by the buffing wheel 6. The type matrices are conveniently held 30 during the cleaning operation by a frame generally designated as 30. This frame comprises side members 31 and end members 32 and 33, secured together by screws 34. Between the end members, partition strips 35 extend spaced apart the length of the type matrices 35, as shown more particularly in Fig. 10.

The matrices are held in place by clamping screws 36, arranged at the end of each 40 row of matrices. Each screw 36, is provided with a flanged head 37, for sliding engagement with a T-slot 38, in one face of a block 39, adapted to bear against the matrices in that section of the frame.

45 As it is desirable that the buffing or other wheel 6, should not contact with the letters on the matrices, means are preferably provided for shielding the letters during the cleaning operation. This may conveniently be accomplished by means of a grid 41, provided with a series of bars 42, adapted to extend over the line of letters in each row of matrices as shown more particularly in Fig. 10.

55 This grid 41, is conveniently retained in position over the frame 30, by means of depending flanges 43, at each end and lugs 44 at each side. Slots are formed in one of the flanges 43, at each end and lugs 44, at each side. Slots are formed in one of the flanges 43, for the reception of the screws

36. Slots are also arranged adjacent the center of each flange so that the latter may be brought into engagement with the heads of clamping screws 45.

65 The operation is as follows:

The screws 36 of the matrix frame 30, are loosened to draw back the blocks 39. A series of matrices are then arranged in each section of the frame while the latter is resting on a table or other flat surface. Then the screws 36, are tightened to clamp each row of matrices in position. Next the grid 41, is slid over the frame 31 and secured thereto by turning the screws 45.

75 The frame 30, is then placed on the table 24, beneath the wheel 6 with its partitions 35, substantially parallel to the plane of the wheel and adjusted to the proper height by means of the screw 21. The frame is then 80 moved under the wheel, either by sliding it over the table or else by swinging the table 24 and bracket 11, about the standard 1. After cleaning the tops of the matrices, the frame may be turned over to clean the 85 bottom.

I am aware that many changes may be made, and numerous details of construction may be varied through a wide range without departing from the principles of this 90 invention, and I therefore do not purpose limiting the patent granted hereon otherwise than necessitated by the prior art.

I claim as my invention:

1. A device of the kind described comprising a frame adapted to hold a series of type matrices, means for locking the matrices in position in the frame and a cover strip adapted to extend over the letter on each matrix and leave the parts on either side 95 thereof exposed.

2. A device of the kind described comprising a frame adapted to hold a series of type matrices, and a cover strip adapted to extend over the letter on each matrix and leave the parts on either side thereof exposed.

3. A device of the kind described comprising a frame adapted to hold a plurality of rows of type matrices, and a grid adapted to fit over said frame, the bars of the grid being arranged to extend over the letter on each of the matrices and leave the parts on either side thereof exposed.

110 In testimony whereof I have hereunto subscribed my name in the presence of two subscribing witnesses.

RUTHERFORD B. CHASE.
